UNITED STATES PATENT OFFICE.

WILLIAM GRUNOW, OF NEWARK, NEW JERSEY, ASSIGNOR TO SPLITDORF ELECTRICAL COMPANY, OF NEWARK, NEW JERSEY, A CORPORATION OF NEW JERSEY.

IGNITION DEVICE FOR INTERNAL-COMBUSTION ENGINES.

Application filed April 7, 1919. Serial No. 288,152.

To all whom it may concern:

Be it known that I, WILLIAM GRUNOW, a citizen of the United States, residing at Newark, in the county of Essex, State of New Jersey, have invented certain new and useful Improvements in Ignition Devices for Internal-Combustion Engines, of which the following is a description, reference being had to the accompanying drawing and to the figures of reference marked thereon.

The invention relates to new and useful improvements in ignition devices, and more particularly to an ignition device having a fixed and a movable electrode, to which current is supplied by a magneto generator.

An object of the invention is to provide an ignition device of the above character, which includes independent supporting brackets, one of which carries the electrodes and the other the magneto generator, and to provide one of said brackets with an opening which is adapted to fit about the other bracket so as to positively hold the brackets in fixed relation to each other, whereby proper synchronism in the movement of the current generating member and the movable electrodes may be insured and whereby when the brackets are replaced, after having been removed for any purpose, they will be positioned in precisely the same relation to each other as before removal, so that the synchronism of the parts will be insured.

A further object of the invention is to provide an ignition device of the above character with independent supporting brackets, one of which carries the electrodes and the other the magneto generator and to provide means for positioning said brackets relative to each other and also to provide a construction of bracket for the magneto generator which may be readily made from stamped sheet metal.

These and other objects will in part be obvious and will in part be hereinafter more fully disclosed.

In the drawings which show by way of illustration one embodiment of the invention—

Figure 1 is a view partly in side elevation and partly in section, showing my improved brackets with the parts of the ignition device assembled thereon;

Figure 2 is a front view of the same, but

showing the magneto generator removed;

Figure 3 is a top plan view of the parts shown in Figure 2;

Figure 4 is a view showing the blank so as to form the bracket for supporting the generator.

The invention consists broadly in a supporting means for the electrodes and the magneto generator. In the present embodiment of the invention, I have provided two supporting brackets which are entirely independent of each other in the sense that when the brackets are removed from the engine they are disconnected. On one of the brackets is mounted the electrodes and one of the electrodes is preferably movable, relative to the other, for producing a spark. On the other bracket is mounted the magneto generator. The bracket for supporting the magneto generator is formed of sheet metal, which is cut into proper shape and then bent so as to provide a supporting base part which is adapted to be attached to the engine cylinder, and a projecting shelf on which the magneto generator is mounted. This sheet metal blank from which the bracket is formed is provided also with suitable lugs to which the generator may be bolted and suitable projecting arms which serve to support certain of the parts cooperating with the actuating devices.

The supporting base of the bracket is formed with an opening which is adapted to receive the projecting end of the igniter block and the projecting end of the igniter block is shaped to conform with the opening in the bracket, so that when the projecting end of the igniter block is placed within said opening, said igniter block will have a definite predetermined position relative to the bracket carrying the generator. Preferably, the two brackets are secured to the engine cylinder by the same bolts which pass through alined holes in the two brackets.

By this construction the two brackets may be removed from the engine cylinder and when removed they are separate and independent of each other. The bracket carrying the movable electrodes may be immersed in gasoline, or any other cleaning fluid, and the electrodes thoroughly cleaned. After the parts have been thoroughly

cleaned, the brackets may be replaced on the engine and this interfitting of one bracket within the other insures the replacement of the brackets in exactly the same relation to each other as before they were removed and thereby the synchronism of the parts—that is, the movable current generating member and the movable electrode will not be disturbed.

Referring more in detail to the drawings, my improved ignition device consists of a sheet metal supporting bracket 1, on which the magneto generator, indicated at G, is mounted, and a second supporting bracket 2, in which the electrodes are mounted. The fixed electrode is indicated at 3 in the drawings, and the movable electrode is indicated at 4. These electrodes are provided with the usual igniter points which are brought into engagement and are separated to produce a spark. The bracket 2 has a projecting flange 5, which is formed with bolt holes 6, through which bolts 7—7 are adapted to be passed, which bolts are threaded into the engine cylinder, indicated at C in the drawings. A suitable pad 8 may be used in order to make the joint between the igniter block or bracket and the cylinder a tight joint.

In Figure 4 of the drawings, I have shown the blank 1 after it is stamped and before it is folded in order to produce the bracket. Said blank has a part 9 which forms the supporting base for the bracket. Projecting outwardly from this base 9 are arms 10—10 which are bent at right angles to the supporting base and into parallel relation to each other. The end portions 11—11 of the arms are then bent at right angles to the arms 10—10, and may be riveted together or welded together, or secured in any other suitable way, thus forming a strengthening connection between the arms. Projecting from the arms 10—10 are auxiliary arms or lugs 12—12. These are bent downwardly into a horizontal plane, as indicated in Figure 1, and bolts 13—13 pass through suitable openings, respectively, formed in said arms and these bolts are threaded into the base of the generator G and serve as a means for firmly securing the generator to the arms 10—10. As clearly shown in Figure 2 of the drawings, the generator is directly above these parts 12—12 and also directly above and rests upon the arms 10—10. The generator is provided with a current generating member, such as an armature, and the shaft of this current generating member is indicated at 14 in the drawings. Secured to this shaft 14 is a sleeve 15, which is formed with a downwardly projecting arm 16 adapted to be engaged by a push rod 17, the end of which is indicated in dotted lines in Figure 2.

Fixed to the shaft carrying the movable electrode 4 is a sleeve 18. A spring 19 sur-

rounds the sleeve 18 and is fixed at one end to a pin 20 carried by said sleeve 18. This spring is secured at its other end to the arm 16 and serves as a means for rotating the armature. The sleeve 15 is provided with a projecting tooth 21, which is adapted to co-operate with a projecting tooth 22 on the sleeve 18.

A post 23 is secured to an arm 24 formed as a part of the bracket 1, and this post is provided with a spring buffer 25 against which the arm 16 normally rests.

A second arm 24^a is provided and welded or otherwise secured to the arm 24, when the bracket has been bent into proper form, so as to strengthen the arm 24 to prevent the same from being bent out of its proper plane due to percussions on the post 23.

The actuating mechanism for the generator and the movable electrode form no part of my invention and further detail description thereof is not thought necessary. It may be stated that the push rod 17 operating upon the arm 16 compresses the spring 19 which forces the electrodes together, and when the arm 16 is tripped by the push rod being knocked off from engagement therewith, the spring will rotate the sleeve 15 until the arm 16 strikes the buffer and as this buffer is yieldable, it will give so that the sleeve 15 will move to a point to bring the tooth 21, carried thereby, into engagement with the tooth 22 on the sleeve 18, and this will rotate the sleeve 18 sufficiently to separate the electrodes to produce a spark. The yielding buffer moves the tooth 21 out of engagement with the tooth 22 when the parts resume their normal position and the spring 19 will hold the contacts together, so that normally the contact points are together and properly shielded from carbon deposit and they are separated by the action of the main spring in the manner above stated. The operating mechanism of the magneto and electrodes forms no part of my present invention, but is shown, described and claimed in Patent 1,370,934 issued March 8, 1921 to Harry R. Ven Deventer.

The base portion 9 of the bracket has its lower edge 26 bent so as to rest against the engine cylinder. This forms a very durable support for the bracket and also forms a housing within which a rod 27 may slide, said rod carrying the push rod proper 17.

The supporting base 9 of the bracket 1 is formed with bolt holes 28. These bolt holes are in alinement with the bolts 6 in the bracket 2, and the bolt holes 7—7 pass through the bolt holes, so that both brackets are secured by the same bolts.

It will be obvious from the above description that I have provided an ignition device, wherein the magneto generator is carried by a bracket which is entirely independent of the bracket which supports the

electrodes, and yet the two brackets when assembled in the engine will always have a fixed definite relation to each other and this relation can not be disturbed through the 5 working loose of the bolts which support the brackets on the engine cylinder. After once the parts are adjusted for proper synchronism, the brackets will always maintain the same fixed relation to each other during the 10 operation of the engine, and, if the brackets are removed for the purpose of cleaning the electrodes, or for the purpose of replacing the electrodes, then the brackets when replaced will always be set in this same fixed 15 relation to each other that they had when the parts were adjusted, and, therefore, the synchronism of the parts will not be disturbed. Furthermore, it is sometimes desirable to replace the electrodes, and by my 20 improved construction, where the igniter block is independent of the main bracket supporting the generator, this igniter block may be quickly replaced without requiring the use of a new bracket for the generator. 25 Also, by my improvement the generating supporting bracket may be made of sheet metal. Where brackets of this character are cast they are often very weak, owing to some defect in the casting, and readily become 30 broken. By my improvement, however, where the bracket is formed of sheet metal, these imperfections in construction are completely avoided. Each bracket will be 35 strong and durable and at the same time may be cheaply made.

It is to be noted that the bracket 2 is provided with a projection 2^a which extends into and fits the rectangular shaped opening 1^a in the bracket 1. This opening in the 40 bracket 1 fitting the projection 2^a insures that the two brackets when placed together will have a predetermined fixed position relative to each other irrespective of the size of the bolt holes. When the brackets are 45 removed from the engine they at once become separated but when replaced on the engine the projection fitting into the opening will reposition the bracket 1 in exactly the same position in which it was set before 50 it was taken off the engine. This enables the synchronism of the parts to be restored or maintained when the brackets are replaced after they have been separated or taken from the engine. On the other hand, 55 the brackets may readily be separated and the part carrying the electrodes immersed in gasoline for cleaning, as noted above.

While I have an opening in one bracket surrounding a projection on the other, it 60 will be understood that my invention is not limited to the particular way in which I bring about this positioning of one bracket relative to the other and that various ways will at once suggest themselves for maintaining or repositioning the brackets so that they

will be in exactly the same predetermined position as they were when removed from the engine.

It is obvious that minor changes in the 70 details of construction and the arrangement of parts may be made without departing from the spirit of the invention, as set forth in the appended claims.

Having thus described my invention, what I claim as new and desire to secure by Letters Patent, is:

1. An ignition device including in combination, a supporting bracket, a fixed and a movable electrode carried thereby, a second supporting bracket, a magneto generator carried by said second bracket, and means for securing the brackets to the engine cylinder, said bracket for the magneto generator having an opening formed there- 80 in adapted to surround and closely fit a projecting part of the supporting bracket for the electrodes, whereby said brackets are held in fixed relation to each other. 85

2. An ignition device including in combination, a supporting bracket, a fixed and a movable electrode carried thereby, said supporting bracket having a forwardly projecting portion and a flange portion formed with bolt holes, a second supporting bracket, a magneto generator carried by said second bracket, said second bracket having an opening formed therein adapted to surround and closely fit the projection on the first named bracket and having bolt holes in alinement with the bolt holes in the first named bracket, whereby bolts may be inserted into the engine cylinder for securing both brackets thereto. 95

3. An ignition device including in combination, a supporting bracket, a fixed and a movable electrode carried thereby, said supporting bracket having a forwardly projecting portion, a second bracket, a magneto generator mounted thereon, said second bracket having a supporting base provided with an opening surrounding and closely fitting the forwardly projecting portion of the first named bracket, said second bracket having a shelf formed integrally with said base portion on which the magneto generator is mounted, and means for securing said brackets to the engine cylinder. 100 110 115

4. An ignition device for an internal combustion engine including in combination, a supporting bracket having flanges and a part projecting forwardly of said flanges, electrodes mounted in said bracket, a stamped sheet metal bracket having a base portion fitting over said flanges and having an integral shelf on which said magneto is mounted, said base portion having an opening of considerable area therein for dowelling with said forwardly projecting part of the first mentioned bracket and means passing through said base portion and 120 125 130

said flanges for holding both said brackets in operative relation and to the engine.

5. An ignition device including in combination, a magneto generator, a supporting bracket therefor, said supporting bracket being formed of stamped sheet metal, shaped and bent so as to form a supporting base, and parallel arms projecting from the sides of said supporting base, said arms 10 being secured together at their forward ends and having inwardly projecting perforated lugs through which bolts may be inserted for securing the magneto generator on said arms.

15 6. A sheet metal bracket for a magneto generator ignition device comprising a supporting base having the lower edge inturned and resting against the engine cylinder, arms projecting from the opposite sides of 20 said supporting base and in parallel relation to each other, inwardly projecting perforated lugs through which the bolts may be passed for securing the generator to said arms, said arms having their extreme outer 25 ends bent toward each other and connected together.

7. A sheet metal bracket for a magneto generator ignition device comprising a supporting base having the lower edge inturned 30 and resting against the engine cylinder,

arms projecting from the opposite sides of said supporting base and in parallel relation to each other, inwardly projecting perforated lugs through which the bolts may be passed for securing the generator to said 35 arms, said arms having their extreme outer ends bent toward each other and connected together, one of said arms having an inwardly projecting lug on which a post may be supported carrying a part co-operating with 40 the operating mechanism for the magneto.

8. A sheet metal bracket for a magneto generator ignition device comprising a supporting base having the lower edge inturned 45 and resting against the engine cylinder, arms projecting from the opposite sides of said supporting base and in parallel relation to each other, inwardly projecting perforated lugs through which bolts may be passed for securing the generator to said 50 arms, said arms having their extreme outer ends bent toward each other and connected together, said supporting base having a rectangular opening formed therein adapted to receive a projecting part on the bracket on 55 which the electrodes of the ignition device are mounted.

In testimony whereof, I affix my signature.

WILLIAM GRUNOW.
